LUTHER E. ROBY, OF PEORIA, ILLINOIS.

ATTACHMENT MECHANISM.

Application filed March 19, 1926, Serial No. 95,908. Renewed March 3, 1927.

This invention relates to attachment mechanism between plows and drills.

One of the objects of the invention is in the provision of attachment means between

5 plows and drills which insures the travel of the drill behind the plow in the proper drilling position at all times, and further permits the making of a sharp turn when the length of the field has been traversed.

10 Another object is in the provision of special attachment means between a plow and a small drill, adapted to be drawn behind the plow in a manner to insure the proper drilling and seeding operation, said

15 attachment mechanism being of a semi-rigid construction and permitting a sharp turn to be made by the drill.

A further object is in the provision of attachment means between a plow and drill, 20 said attachment mechanism including a semi-rigid positioning of the drill tongue with the plow member and connections with the drill to permit sharp turning thereof.

Other objects of the invention will appear 25 in the following specification, taken in connection with the annexed drawings, in which—

Fig. 1 is a plan view of a plow and following drill member, with the attachment 30 mechanism connecting same;

Fig. 2 is a side elevation of the parts shown in Fig. 1.

Referring to the drawings, there has been shown a special attachment means between 35 a plow and drill, said connecting means insuring proper travel of the drill, as well as permitting sharp turning thereof when necessary.

The necessity for the attachment mechanism which forms the basis for the present 40 application, has apparently arisen only in the past few years, during which time there has come into use, especially in the Northwestern portion of the United States, a

45 manner of plowing and drilling, utilizing a conventional plow member followed by a small drill. Plowing and drilling are ordinarily separate operations, but for the purposes of economy, saving of time, and 50 the employment of less man power, it has been found profitable to combine the use of a plow member with a small drill, properly spaced therebehind in such manner that the drilling operation succeeds immediately the 55 plowing operation.

Connecting means of ordinary design be-

tween the plow and drill will not permit the most efficient functioning and travel of the drill member, and for this reason, applicant has devised the following mechanism.

60 10 designates a well known three-bottom plow structure, the same being of conventional design. 11 generally refers to a small press drill, conventional in design, except that the drill is considerably smaller 65 than the drill used when a separate drilling operation is employed. The drill 11 is of such size as to properly drill and seed the furrows opened by the three-bottom plow, generally referred to as 10.

70 Referring to the attachment means between the plow and drill, we find the tongue 12, pivotally attached, as at 13, to a framing 14, on the forward end of the drill 11. A sort of fifth wheel construction 15, is employed to control the travel of the tongue 12, and operates to permit short turning of the drill member, when the plow is turned in a similar manner. Stop members 16 and 17 operate to limit the travel of the tongue on 75 the wheel 15, and hence the turning movement of the drill.

80 In view of the fact that the drill must follow in a certain position behind the plow, there must necessarily be a rigid, or substantially rigid, maintenance of the position of the tongue 12, with respect to the plow. This rigid connection is accomplished in the following manner.

85 A clamp 18 is bolted, as at 19 and 20, to 90 the plow beam. This clamp has an outwardly extending bracket 21 having an aperture therein, through which is projected a downwardly extending lug 22, suitably bolted by the series of bolts 23, to the forward end of the tongue 12. This connection is obviously rather loose. A second clamp 24 is fastened by means of the bolt 25, to a brace rod 26 on the plow. The clamp 24 has an extended bracket 27, 95 through which is projected the end of a rod member 28, a conventional cotter pin 29 completing the connection in exactly the same manner as the cotter pin 30 completes the connection of the tongue with the before described clamp 18.

100 Surrounding the rod 28 is a sleeve 31, which abuts at one end the upstanding portion 27, and at the opposite end a bracket 32, securely clamped, as at 33, to the tongue 12. The rod member 28 projects through 110 an aperture in the bracket 32, permitting the

above described abutment of the sleeve with said bracket.

Means for providing a semi-rigid connection of the tongue with respect to the plow is 5 accomplished by the use of the coil spring 34 surrounding the projecting end of the rod 28, there being provided a washer 35 attached to the projecting end of the rod 28, securing one end of the coil spring 34, the 10 other end abutting bracket 32.

The operation of the attachment means herein shown between the plow and drill is thought obvious, in view of the above description, except for the fact that although 15 the drill member is maintained in a substantially rigid position behind the plow, to insure proper operation, nevertheless, there is provided the spring tensioned connection of the tongue with the plow to take care 20 of the movement of the drill over extremely uneven ground surface and over rocks and the like.

Due to the use of this attachment means, insurance of proper travel of the drill behind the plow is effected, and the special 25 connection of the tongue with the drill permits turning of the drill member in direct relation to the turning of the plow.

What I claim is:

30 1. The combination with a plow and a drill member, of attachment means therebetween adapted to insure travel of the drill in alignment with the plow, as well as permitting short turning radius, including a 35 tongue attached to the plow and having a pivotal connection, at a point near its opposite end, with the drill, framing members

disposed rearwardly of the pivotal connection with the drill, said framing members controlling the movement of the tongue with respect to the drill member, stop members on the framing members to limit the turning movement of the drill with relation to the tongue, and mechanism connecting the plow with the tongue to hold the latter in a semi-rigid manner with respect to the plow. 40 45

2. In apparatus of the character described, a gang plow main frame, a main draw bar centered forwardly thereof, a set of plows carried by the main frame and having its mean point of draft located at one side of the longitudinal axis of said frame, a second draw bar carried by the frame at the opposite side of its longitudinal axis, a tilling implement pivotally connected to said second draw bar by a tongue, and semi-resilient means between said main frame and said tongue to normally hold the tongue substantially parallel with the main frame, thus causing the main draw bar pull to normally pass through said longitudinal axis. 50 55

3. The combination with a plow and a drill member, of attachment means therebetween adapted to insure travel of the drill in alignment with the plow, as well as permitting short turning radius, including a tongue attached to the plow and to the drill, and mechanism connecting the plow with the tongue to hold the latter in a semi-resilient manner with respect to the plow. 60 65 70

In testimony whereof, I have hereunto affixed my signature.

LUTHER E. ROBY.
